UNITED STATES PATENT OFFICE

2,480,813

REFRIGERANT FLOW CONTROLLING
DEVICEDavid C. Prince, Schenectady, N. Y., assignor to
General Electric Company, a corporation of
New York

Application January 3, 1948, Serial No. 425

15 Claims. (Cl. 62—8)

1 My invention relates to refrigerating systems and more particularly to flow controlling arrangements for refrigerating systems.

In the operation of mechanical refrigerating systems various types of flow controlling arrangements may be employed. For example, float valves have been utilized for controlling the supply of liquid refrigerant to evaporators of mechanical refrigerating systems. Such valves provide a positive control of the flow of refrigerant but it has been necessary to provide a separate unloading arrangement to allow the compressor motor to come up to speed. An alternative arrangement employs a restricted tube, sometimes referred to as a capillary tube, between the condenser and the evaporator for controlling the flow of refrigerant. Where such restricting tubes are employed it is not necessary to provide separate unloading means, but another difficulty has arisen in some systems having restricting tubes in that, because of the very small diameter of the restricting tube, even a small amount of moisture in the system may freeze within the tube and block the passage therethrough. By my invention a flow control device is provided which has the advantage of the positive control feature of the float valve and which also combines provision for unloading so that a separate unloading device is rendered unnecessary.

Accordingly, it is an object of my invention to provide a refrigerating system including an improved arrangement for controlling the flow of refrigerant and for unloading the compressor.

It is another object of my invention to provide an improved flow controlling device incorporating a valve and an unloading arrangement.

It is a further object of my invention to provide an improved flow controlling device including an arrangement for varying the operation of the device in accordance with changes in condenser temperature or ambient temperature.

Further objects and advantages of my invention will become apparent as the following description proceeds and the features of novelty which characterize my invention will be pointed out with particularity in the claims annexed to and forming part of this specification.

For a better understanding of my invention reference may be had to the accompanying drawing in which Fig. 1 is a generally schematic representation of a refrigerating system incorporating my invention; Fig. 2 is a sectional view of details of the flow controlling device shown in Fig. 1; and Fig. 3 illustrates a modification of my invention.

2 Referring now to Fig. 1, the refrigerating system there illustrated includes a compressor 1, a condenser 2, and an evaporator 3. The compressor is arranged within a hermetically sealed casing 4 and is driven by a suitable electric motor (not shown) also included within the hermetically sealed casing 4. Compressed refrigerant is supplied to the condenser through a conduit 5 and vaporized refrigerant is returned to the casing 4 through a suction line 6. Heat is removed from the compressed refrigerant by air passing over the condenser.

3 In order to control the flow of liquid refrigerant from the condenser 2 to the evaporator 3, the valve 7 is provided in the liquid line connecting the condenser and the evaporator. The condenser is connected to the valve through a conduit 8, and a conduit 9 provides communication between the valve and the evaporator.

4 Within the casing 4 and on the same shaft as the compressor 1 there is arranged a rotary oil pump 10 which supplies lubricating fluid to the compressor. This pump is driven by the same electric motor as is utilized for driving the compressor 1. Lubricating fluid is also supplied from the pump 10 through the passages 11 and 12 and a conduit 13 to the valve 7. Since the pump and the compressor are driven simultaneously by the same motor, whenever the compressor is in operation, lubricating fluid under pressure is necessarily supplied to the valve 7 through the passages described. Conversely, when the compressor is not in operation, the pump 10 is stationary and the lubricating fluid is not under pressure.

5 In Fig. 2, details of valve 7 are illustrated. The valve 7 includes a valve body 14 having a passage 15 communicating with the conduit 8 and a passage 16, communicating with the conduit 9. Within the valve body adjacent the passages 15 and 16 a seat 17 is provided and a movable valve element 18 is arranged for engagement with the seat 17.

6 The valve includes a housing 19 which is composed of two cooperating hollow cylindrical parts 20 and 21. The part 20 is arranged for screw threaded engagement with the valve body 14 as indicated by 22, and the assembly of the valve housing is completed by screw threaded engagement between the parts 20 and 21 of the housing, as indicated by 23.

7 In order to control the movement of the valve element 18 by providing a proper biasing force during operating periods and to remove this biasing force for unloading purposes during non-

Operating periods, a control device is arranged within the valve housing 19. The housing part 21 provides a chamber 24, and the conduit 13 is connected to the housing in communication with the chamber 24 so that lubricating fluid from the pump 10 may be supplied to the chamber 24. A hollow piston 25 is slidably received within the chamber 24 and is adapted to be moved under the influence of the pressure of the lubricating fluid. A cup-shaped member 26 is also arranged within the housing 19 and is slidably received within the hollow piston 25.

A bellows 27 is secured to the end of the valve element 18 and one end of the bellows is sealed to the valve body 14 as indicated by 28. The bellows allows movement of the valve between the open and closed positions but, by reason of its being sealed to the valve body 14, it effectively prevents leakage of refrigerant from the system at the valve element. In order to transmit motion from the cup-shaped member 26 to the bellows 27 and to the valve element 18, a calibrating screw 29 is provided. This screw extends into engagement with a threaded recess in the end of the cup-shaped member 26 and the head of the screw is arranged to engage the bellows 27 adjacent the end of the valve element 18. The opposite end of the screw 29 engages a compression spring 30 which extends internally between the piston 25 and the cup-shaped member 26. The calibrating screw may be turned by any suitable wrench inserted through an opening 31 in the valve housing to vary the compression on the spring 30 for normal operation. In order to maintain the compression spring in position, the hollow piston 25 is provided with an internal tubular guide portion 32 and the cup-shaped member 26 includes a corresponding internal guide portion 33. The guide portions 32 and 33 support the spring along the major portion of its length and minimize lateral movement thereof.

In the position shown in Fig. 2, the compression spring exerts a force tending to bias the valve element 18 to its closed position, the force exerted being dependent upon the characteristics of the spring. Thus, the valve is maintained in its closed position until the pressure differential between the condenser and evaporator exceeds the force exerted by the spring. Under this latter condition, the valve is forced to its open position against a bias of the spring, and liquid refrigerant is supplied to the evaporator until the pressure differential is reduced to a value equal to the force exerted by the spring. Thus, the valve maintains a pressure in the condenser sufficient to effect condensation of the compressed refrigerant supplied by the compressor 1.

When the compressor stops at the end of an operating cycle, it is desirable to provide for reduction or elimination of the pressure differential between the condenser and the evaporator so that, at the beginning of the next operating cycle, the compressor is permitted to start under a relatively light load. Should the pressure differential be maintained at its normal operating value, the compressor, in starting, would have to supply a refrigerant against the high pressure existing in the condenser, and this would impose an undesirably heavy load on the motor driving the compressor. By my invention, provision is made for automatically reducing the pressure in the condenser when the refrigerating apparatus stops at the end of an operating cycle. During operating periods, the piston 25 may be maintained in the position shown in Fig. 2 under the influence

of the pressure of the lubricating fluid within the chamber 24. When the compressor stops, the pump 10, which is driven by the same motor as the compressor, also stops, and the pressure of the lubricating fluid is accordingly reduced. Under these circumstances, the piston 25 moves to the left, reducing the compression upon the spring 30. This correspondingly reduces the force exerted by the spring on the valve element 18, and the pressure differential between the condenser and the evaporator normally maintained by this valve is accordingly reduced. Preferably, an elongated opening 34 is provided in the cup-shaped member 26 and a pin 35, which is threaded through an opening in the hollow piston 25, extends into the opening 34. The pin engages an end of the elongated opening to limit the movement of the piston to the left. This prevents the piston from engaging the end of chamber 24 and thereby insures the relieving of biasing force on the valve regardless of whether the spring is completely relaxed or not.

The arrangement described above has the effect of reducing the condenser pressure and therefore unloading the refrigerating apparatus. Hence, when the compressor starts at the beginning of the next operating cycle, it operates under a light load until the pressure of the lubricating fluid has built up to a sufficient degree to move the piston 25 to the right to the position shown in Fig. 2. During this time, the driving motor for the compressor has had an opportunity to come up to the operating speed and the refrigerating apparatus is able to assume the full operating load without any overloading of the motor.

It can be seen that by my invention the operation of a controlling valve is modified to provide for unloading and that, as an additional feature, this is accomplished by utilizing an element already required for other purposes, namely, the lubricating pump of the refrigerating apparatus.

In order to vary the biasing force exerted on the valve with changes in temperature conditions so that the pressure maintained in the condenser will be satisfactory for the particular temperature conditions involved, a compensating device operated in accordance with changes in temperature is provided. As illustrated in Fig. 2, the compensating device is arranged to be primarily responsive to changes in the temperature of the condenser 2; however, the compensating device is also dependent upon changes in ambient temperature, since such changes are a primary factor in variations in the temperature of the condenser, which is cooled by the circulation of air at ambient temperature thereover. The compensating device includes a pivoted lever 36. This lever is mounted by a pin 37, and a screw threaded element 38 on a support 39 extending upwardly from the valve housing 19. The screw threaded element 38 engages internal threads within the support 39 in order to provide for adjustment of the position of the pivot pin 39, and hence, of the lever 36. This adjustment is provided for calibrating purposes and is primarily utilized in the initial installation of the compensating device. The pivoted lever 36 includes a plurality of stops or notches 40, 41, 42 and 43 along one face, these stops being disposed adjacent a post 44 extending outwardly from the hollow piston 25. The post 44 is formed integral with a side of the piston 25 and extends outwardly through an elongated opening 45 in the valve housing 19. For engagement with the stops

On the pivoted lever, an adjustable screw 46 is provided, and this screw extends into engagement with an internal threaded portion of the post 44. The screw 46 is made adjustable for calibrating purposes so that it may be adjusted along with the screw threaded element 38 during the initial installation of the compensating device.

In order to shift the pivoted lever 36 in accordance with change in condenser temperature, the conduit 8, which is connected to the condenser, includes a portion 47 surrounding the main portion of the conduit adjacent the pivoted lever 36. The portion 47 is secured to the main portion of the conduit 8 at 48 and includes a flanged portion 49 which extends into engagement with an end 50 of the pivoted lever 36. The portion 47 is composed of a material having a greater coefficient of expansion than the material of which the main portion of the conduit 8 is composed.

The operation of the compensating device is as follows. Within a particular range of condenser temperatures, the pivoted lever 36 assumes the position shown in Fig. 2. In this position, the head of the screw 46 has moved to the right along with the piston 25 upon which it is mounted, under the influence of the pressure of the lubricating fluid in the chamber 24, and the head of the screw has come into engagement with stop 42 of the pivoted lever. This stop limits the movement of the piston 25 and, accordingly, limits the compression of the spring 30 resulting from the movement of the piston. Hence, there is a predetermined maximum biasing force on the valve element 18, and a corresponding pressure differential between the condenser and the evaporator is maintained by the valve. Should the condenser temperature increase beyond this range, necessitating the operation of the condenser at a somewhat higher pressure, the resulting expansion of the portion 47 causes the lower end thereof to move downwardly, thereby moving the lever 36 in a clockwise direction. This moves the stop 42 upwardly beyond the head of the screw 46 and allows the piston 25 to move farther to the right under the influence of the pressure of the lubricating fluid in the chamber 24, positioning the head of the screw against the stop 43. This movement of the piston 25 further compresses the spring 30 and therefore results in an increased biasing force on the valve element 18 and a corresponding increase in the condenser pressure.

Conversely, should the condenser temperature decrease, the pivoted lever 36 is moved in a counterclockwise direction by a tension spring 51 to position either the stop 41 or the stop 40 for engagement by the head of the screw 46. It will be noted that this change cannot occur during an operating period of the apparatus, since the screw 46 prevents counterclockwise movement of the pivoted lever 36 in the position of the piston 25 shown in Fig. 2. The pivoted lever does not shift to its new position as a result of the decrease in condenser pressure until the piston 25 has moved to the left to carry the screw 46 beyond the stop 40 of the pivoted lever at the end of an operating period. However, since the operating period of the apparatus is normally of short duration, particularly as compared to the time required for any substantial ambient temperature change which would affect the operating temperature of the condenser, this factor does

not affect the satisfactory operation of the compensating device.

Fig. 3 illustrates a modified arrangement for accomplishing the movement of the pivoted lever in compensating for changes in temperature. A thermostatic bulb 52 is positioned so as to be responsive to condenser temperature or to ambient temperature, and the bulb is connected by a tube 53 to an expansible bellows 54, the bellows being mounted on a suitable stationary support 55. A rod 56 is connected to the movable end of the bellows 54, and the lower end of the rod 56 bears against a pivoted lever 36', corresponding to the lever 36 in Fig. 2. In order to prevent lateral deflection of the rod, a stationary support 57 is provided, this support including a guide portion 58 for receiving the rod 56.

The operation of the modified form shown in Fig. 3 is essentially the same as that shown in Fig. 2. The bulb 52, as mentioned above, may be placed so as to be responsive to either ambient temperature or condenser temperature. If the bulb is located so as to be responsive for example to ambient temperature, then should the ambient temperature increase, the bellows 54 expands. The rod 56 is moved downwardly by the expansion of the bellows and causes a clockwise movement of the pivoted lever 36'. This moves stop 42' upwardly and allows the screw 46 to move to the right into engagement with stop 43', increasing the compression on the spring 30 (not shown in Fig. 3) and the biasing force on the movable valve element 18. Conversely, should the ambient temperature decrease, the bellows contracts and, at the end of the operating period the pivoted lever 36' is moved by the tension spring 51 in a counterclockwise direction against the end of the rod 56. The head of the screw 46 is then positioned in engagement with the stop 41' or the stop 40', and the biasing force on the valve is reduced.

While I have shown and described specific embodiments of my invention, I do not desire my invention to be limited to the particular constructions shown, and I intend by the appended claims to cover all modifications within the spirit and scope of my invention.

What I claim as new and desire to secure by Letters Patent of the United States is:

- 50 1. A refrigerating system including a compressor, a condenser, and an evaporator, a valve for controlling flow of refrigerant from said condenser to said evaporator, pumping means dependent on the operation of said compressor for supplying fluid under pressure to said valve, and means responsive to the pressure of said fluid for exerting a force biasing said valve toward its closed position to maintain a pressure differential between said condenser and said evaporator.
- 55 2. A refrigerating system including a compressor, a condenser, and an evaporator, a pump driven simultaneously with said compressor, a valve for controlling flow of refrigerant from said condenser to said evaporator, means for conveying fluid from said pump to said valve, and means responsive to the pressure of said fluid for exerting a force biasing said valve toward its closed position to maintain a pressure differential between said condenser and said evaporator.
- 60 3. A refrigerating system including a compressor, a condenser, and an evaporator, a pump driven simultaneously with said compressor, a valve for controlling flow of refrigerant from said condenser to said evaporator, means for conveying fluid from said pump to said valve, a resilient
- 65
- 70
- 75

member for biasing said valve toward its closed position, and means responsive to the pressure of said lubricant for rendering said resilient member effective to maintain a pressure differential between said condenser and said evaporator.

4. A refrigerating system including a compressor, a condenser, and an evaporator, a lubricant pump driven simultaneously with said compressor, a valve for controlling flow of refrigerant from said condenser to said evaporator, means for conveying lubricant from said pump to said valve, a spring for biasing said valve toward its closed position, and means responsive to the pressure of said lubricant for rendering said spring effective to maintain a pressure differential between said condenser and said evaporator.

5. A refrigerating system including a compressor, a condenser, and an evaporator, a valve for controlling flow of refrigerant from said condenser to said evaporator, a spring for biasing said valve toward its closed position, and means responsive to the operation of said compressor for supplying fluid under pressure to said valve to increase the force exerted by said spring, the pressure of said fluid being reduced upon the stopping of said compressor to reduce the force exerted by said spring whereby the bias on said valve is relieved to unload the compressor.

6. A refrigerating system including a compressor, a condenser, and an evaporator, a pump driven simultaneously with said compressor, a valve for controlling flow of refrigerant from said condenser to said evaporator, said valve including a chamber and a piston within said chamber, a spring engaging said piston for biasing said valve toward its closed position, and means for conveying fluid from said pump to said chamber, the pressure of said fluid against said piston acting to shift said piston whereby said spring is rendered effective for maintaining a pressure differential between said condenser and said evaporator.

7. A refrigerating system including a compressor, a condenser, and an evaporator, a pump driven simultaneously with said compressor, a valve for controlling flow of refrigerant from said condenser to said evaporator, said valve including a chamber and a piston within said chamber, a movable valve element, a compression spring arranged between said piston and said movable valve element for biasing said valve element toward its closed position, and means for conveying fluid from said pump to said chamber, the pressure of said fluid against said piston acting to shift said piston whereby said spring is rendered effective to maintain a pressure differential between said condenser and said evaporator.

8. A refrigerating system including a compressor, a condenser, and an evaporator, a pump driven simultaneously with said compressor, a valve for controlling flow of refrigerant from said condenser to said evaporator, means for conveying fluid from said pump to said valve, means responsive to the pressure of said fluid for exerting a force biasing said valve toward its closed position to maintain a pressure differential between said condenser and said evaporator, and temperature responsive means for limiting the biasing force on said valve.

9. A refrigerating system including a compressor, a condenser, and an evaporator, a pump driven simultaneously with said compressor, a valve for controlling flow of refrigerant from said condenser to said evaporator, means for conveying fluid from said pump to said valve, means re-

sponsive to the pressure of said fluid for exerting a force biasing said valve toward its closed position to maintain a pressure differential between said condenser and said evaporator, and means responsive to the temperature of said condenser for limiting the biasing force on said valve.

10. A refrigerating system including a compressor, a condenser, and an evaporator, a pump driven simultaneously with said compressor, a valve for controlling flow of refrigerant from said condenser to said evaporator, means for conveying fluid from said pump to said valve, means responsive to the pressure of said fluid for exerting a force biasing said valve toward its closed position to maintain a pressure differential between said condenser and said evaporator, and means responsive to ambient temperature for limiting the biasing force on said valve.

11. A refrigerating system including a compressor, a condenser, and an evaporator, a pump driven simultaneously with said compressor, a valve for controlling flow of refrigerant from said condenser to said evaporator, said valve including a chamber and a piston within said chamber, means for conveying fluid from said pump to said chamber, said piston being movable under the pressure of said fluid to introduce a force biasing said valve toward its closed position, said piston including a portion projecting beyond said chamber, and means responsive to the temperature of said condenser for engaging said portion to limit the movement of said piston whereby the biasing force exerted on said valve is limited.

12. A refrigerating system including a compressor, a condenser, and an evaporator, a pump driven simultaneously with said compressor, a valve for controlling flow of refrigerant from said condenser to said evaporator, said valve including a chamber and a piston within said chamber, means for conveying fluid from said pump to said chamber, said piston being movable under the pressure of said fluid to introduce a force biasing said valve toward its closed position, said piston including a portion projecting beyond said chamber, and means responsive to ambient temperature for engaging said portion to limit the movement of said piston whereby the biasing force exerted on said valve is limited.

13. A refrigerating system including a compressor, a condenser, and an evaporator, a pump driven simultaneously with said compressor, a valve for controlling flow of liquid refrigerant from said condenser to said evaporator, said valve including a chamber and a piston movable within said chamber, means for conveying fluid from said pump to said chamber, said piston being movable under the pressure of said fluid to introduce a force biasing said valve toward its closed position, said piston including a portion projecting beyond said chamber, and a pivoted lever mounted adjacent said portion and movable in response to changes in the temperature of said condenser, said pivoted lever including a plurality of stops for engaging said portion of said piston in a plurality of positions for varying the biasing force exerted on said valve.

14. A refrigerating system including a condenser, a compressor and an evaporator, a pump driven simultaneously with said compressor, a valve for controlling the flow of refrigerant from said condenser to said evaporator, said valve including a chamber and a piston movable within said chamber, said piston including a portion extending beyond said chamber, a pivoted lever mounted adjacent said portion of said piston, and

a conduit extending from said valve to said condenser said conduit including adjacent said pivoted lever a portion composed of a material having a different coefficient of expansion than the material of the conduit, said portion engaging said pivoted lever for moving said lever in response to changes in the temperature of said condenser to vary the position of said piston whereby the biasing force exerted on said valve is varied.

15. A refrigerating system including a compressor, a condenser, and an evaporator, a pump driven simultaneously with said compressor, a valve for controlling flow of refrigerant from said condenser to said evaporator, said valve including a chamber and a piston movable within said chamber, means for conveying fluid from said pump to said chamber, said piston being movable under the pressure of said fluid to introduce a force biasing said valve toward its closed position, said piston including a portion projecting

beyond said chamber, a pivoted lever mounted adjacent said portion of said piston, said pivoted lever including a plurality of stops for engaging said piston in a plurality of positions of said piston, and an expansible bellows arranged to engage said pivoted lever, said expansible bellows being responsive to ambient temperature for moving said pivoted lever to vary the position of said piston whereby the biasing force exerted on

10 said valve is varied.
